[57] **CLAIM**

The ornamental design for a portable combination loudspeaker and radio mount, as shown.

DESCRIPTION

FIG. 1 is a perspective view of the portable combination loudspeaker and radio mount showing the front and one end thereof;

FIG. 2 is a perspective view showing the rear and the other end of the portable combination loudspeaker and radio mount;

FIG. 3 is a top plan view of the mount as shown in FIG. 1; while

FIG. 4 is an elevational view taken from the upper right-hand side of FIG. 1.
